(No Model.)

W. B. MORRIS.

RAILWAY SAFETY ALARM.

No. 274,635.

Patented Mar. 27, 1883.

UNITED STATES PATENT OFFICE.

WILLIAM B. MORRIS, OF SAN FRANCISCO, CALIFORNIA.

RAILWAY SAFETY-ALARM.

SPECIFICATION forming part of Letters Patent No. 274,635, dated March 27, 1883.

Application filed October 30, 1882. (No model.)

To all whom it may concern:

Be it known that I, WILLIAM B. MORRIS, of the city and county of San Francisco, State of California, have invented an Improved Railway Safety-Alarm; and I hereby declare the following to be a full, clear, and exact description thereof.

My invention relates to a novel safety-alarm for railways; and it consists in the arrangement 10 of a series of levers at intervals in the section of a single track and normally held horizontally, tripping devices at each end of the series for releasing the levers and causing them to be elevated in the track, and devices on approaching locomotives for operating the tripping mechanism to raise the levers for subsequently depressing and readjusting them, and 15 for coming in contact therewith while raised to give warning, all of which will hereinafter fully appear.

The object of my invention is to provide against the danger of collision upon section of a single track by giving notice at the farther end of said section that a train has entered 20 the other end.

Referring to the accompanying drawings, Figure 1 is a perspective view of track, showing mechanism in the road-bed. Fig. 2 is an enlarged view of one of the boxes and its mechanism. Fig. 3 is a side elevation of locomotive, showing devices for engaging with mechanism in road-bed.

Let A represent a section of single railway-track, which, for the sake of this description, 35 may be supposed to be in such locality that trains traveling in opposite directions are liable to pass over it within a short time of each other, rendering it of importance for each engineer to know whether it be clear or not. 40 This section of track may be supposed to be of any length—say, for example, one mile.

In the bed of the road, between the rails, near one end, is an elongated box or casing, B, constructed suitably of cast-iron, and provided with a cover, (not shown,) which should 45 be secured and locked in place. Half-way up the track-section is another such box, C, and at the other end is another, D, thus separating each a distance of half a mile. This distance 50 may be increased or diminished if found de-

sirable. In these boxes are mounted transverse shafts E and E', from which are suspended, by rodsee', heavy weights F F'. At the ends of each box are spring-standards G G', having shoulders a, upon which the weights F F' are adapted to rest when raised to a horizontal position. An end of each of the shafts E projects through the boxes on one side, and a lever, H, is attached to said end. These are so secured as to extend vertically above the road-bed when 60 the weights F are hanging down. With the shafts E', on the other side of the boxes, are connected in like manner similar levers, H'.

At each end of the track-section, though I have shown the device but at one end, is a 65 small casing, I, in the center of the road-bed. Within it is mounted transversely a shaft, h, from which depends a rod or arm, b. A lever, e, is secured to the shaft, and extends up on one side of the box in the same manner as lever H, being held in position by an opposing-spring, d, secured to arm b in the box.

Screwed into the ends of the boxes B, C, D, and I are pipes or conveyers J, in which are carried the operating-wires. A wire, K, commences 75 at the end of arm b, to which it is secured. It thence passes through the protecting-pipe, and is connected with the top of the spring-standing G in the box B. Another wire, K', of the same system, is connected with the shaft E, 80 and thence extends outward through the next section of pipe to the middle box, C, where it is connected with the spring-standard G therein. Another wire, K², is connected with the shaft E in box C and passes through the next 85 pipe, and is connected with spring-standard G in the farther box, D. Now, commencing at the farther end, (on the right of Fig. 1,) to return, after supposing the existence of a box similar to I, from which a wire extends to the 90 first spring-standard, G', in the end of box D, I show a wire, L', connected with shaft E' in said box and extending through the pipe to box C to the spring-standard G', in which it is secured. In like manner a wire, L², extends 95 from shaft E' in box C to spring-standard G' in box B.

Let M represent the locomotive, having a pilot, m. Under the pilot, mounted upon one side of the central longitudinal bar, is a wheel 100

or roller, N, while upon the other side of said bar is pivoted an arm, O, the lower end of which extends down to the same horizontal plane as the wheel N. The upper end of the arm O is connected by a cord, o, with the bell or other alarm in the cab.

In a suitable position upon the locomotive or tender, and upon the side of the central line opposite to that upon which arm O is hung, is 10 pivoted a similar arm, O'. I have here shown it upon the rear of the locomotive. The upper end of this arm is likewise connected with the alarm in the engine by a cord, o'.

The various devices I have thus described 15 and their uses will be better understood by the following description. Suppose a train to be entering upon one end of the track-section A. It runs down lever c, thus releasing the levers H, by which they are raised in a vertical position, as will hereinafter appear. The wheel N 20 under the pilot of the locomotive will run down the first of levers H, by doing which the shaft E is turned to raise its weight F upon the shoulder a of spring-standard G. In this 25 position the weight is supported and the lever H remains down. In like manner the other levers H are run down, and the weights in each box along the line are supported by the spring-standards G. The device is now adjusted up- 30 on one side; and to complete the description I suppose a train coming in the opposite direction after the first train has passed over the track-section A. It runs down all the levers H', so that both sides are adjusted. Suppose, 35 now, a train enters on the track-section from the end over which the first train, before described, passed. It immediately runs down lever c of box I. This causes the shaft h to turn and draw on wire K. This in turn draws 40 back standard G and releases weight F, which, falling, turns shaft E to raise its lever H and draw on wire K', which trips the next weight in box C, raising lever H by said box, and in the same manner, through wire K², the lever 45 H of box D is raised. This is all done instantly. All the levers H are at once elevated. Suppose, now, a train to be about to enter the other end of the track. As it touches the box 50 similar to I and runs down its lever all the levers H' upon the other side are raised, and immediately afterward its arm O comes in contact with the raised lever H of box D, and the alarm is sounded. It may be that at the same moment the first train will be made aware 55 of the danger by its arm O coming in contact with one of the levers H', and thus both engineers will at once know that the track is not clear.

The object of the arm O' upon the locomotive is to provide for the alarm when the train 60 is backing and another is approaching from the rear.

It will be observed that this device will be 65 always adjusted, for each train as it first enters gives notice of its coming, and then suc-

cessively runs down all the levers which it raised, and leaves them ready for the next train.

Having thus described my invention, what I claim as new, and desire to secure by Letters Patent, is—

1. In a railway safety-alarm, successive levers held horizontally in the roadway, devices connecting them, tripping devices arranged at the ends of track-section for automatically releasing them, and a device on the locomotive for operating the tripping devices to release and raise the levers, all arranged and combined substantially as and for the purpose herein described. 75

2. In a railway safety-alarm, successive levers held horizontally in the roadway, devices connecting them, a device on a locomotive for operating the tripping devices to release and raise the levers in the roadway, and a device 85 on a locomotive for coming in contact with the raised levers and giving the alarm, all arranged and combined substantially as and for the purpose herein described.

3. In a railway safety-alarm, successive levers held horizontally on each side of the central line of the roadway, devices connecting those on each side with each other, a tripping device at each end of the track-section, connected each with the levers on one side, devices on approaching locomotives to operate the tripping devices at each end to release and raise the levers and other devices thereon coming in contact with the raised levers and giving the alarm, all arranged and combined 95 substantially as and for the purpose herein described. 100

4. In a railway safety-alarm, the swinging levers H, placed at intervals along the track-section, rocking shafts E, with which the levers are connected, weights F, connected with each shaft, spring-standards G, upon which said weights are supported, wires K' K², connecting each rocking shaft with the spring-standard of the weight beyond, and the tripping device consisting of the swinging lever c, rocking shaft h, having an arm, b, spring d, and wire K, connecting said arm b with the first spring-standard, G, in combination with a device upon the locomotive for running 115 down the lever to rock-shaft h and trip-levers H, and for running down said levers H to readjust them, substantially as herein described. 110

5. In a railway safety-alarm, the series of boxes B C D, having rocking shafts E' E, with 120 levers H H' on the sides and weights F F' within the boxes, the spring-standards G G', for supporting the weights and holding the levers H H' down in the road-bed, the wires K' K² L' L², connecting the shafts E E' each, respectively, with a spring-standard, as shown, the tripping devices at each end, consisting of levers c, shafts h, having arms b and springs d, connecting-wires K between said arms and the first spring-standard at each end, in com- 125 130

bination with means on the locomotive for tripping the levers H H' from each end to cause them to be elevated in the roadway, consisting of the wheel or roller N, and means for coming in contact with said upraised levers, consisting of the swinging arms O O', connected with the alarm mechanism in the

locomotives, all arranged substantially as herein described.

In witness whereof I hereunto set my hand.

WILLIAM B. MORRIS.
